MATCH BOOK

Myron S. Teller, Kingston, N. Y.

Application August 31, 1949, Serial No. 113,421

3 Claims. (Cl. 206—29)

1

This invention relates to match books, and particularly to match books of the type embodying paper covers upon which legends, generally advertisements, are printed.

The general purpose of the invention is to provide a match book embodying the customary match package and a cover of conventional overall dimensions and having relatively foldable panels, so that the book may be used in well known manner, but in which the cover is so modified by incision that the match book, or the match book cover after the matches have been detached, may be utilized in novel ways not heretofore contemplated. Thus by incision the cover may be provided with a tab or tongue adapted to be laterally deflected upon the application of slight pressure to coact with the body of the cover in lightly gripping between them the edge of a paper sheet, so as to be able to function as a bookmark. If the cover is preserved and made use of after the matches of the book have been consumed the effectiveness of the match book as an advertising medium is, of course, increased.

Also the cover is so constructed that one or more matches of the match package may be deflected and the heads thereof passed through the front panel of the cover, that panel having been locally weakened by incision to permit such passage and the stem of the match being frictionally gripped by the edges defined by the incision so that the match constitutes a bracing member holding the two major panels of the cover in fixed spaced relation. When the parts are so arranged the match book resembles an easel of small size and is well adapted to be used as a table place marker. The tongue which enables the cover to eventually function as a book mark may be employed, when the match book is arranged as a place marker, to support a name card, cigarettes or other object.

The invention may be embodied in match books which vary considerably in size and details of construction. One such embodiment is illustrated in the accompanying drawings in which,

Figure 1 is a perspective view of the improved match book, shown in closed condition;

Figure 2 is a plan view of the book, the cover being open;

Figure 3 is an edge view of the match book shown in Figure 2;

Figure 4 shows the cover in plan view in association with a sheet of paper and after the matches have been consumed, the cover being in use as a bookmark; and

Figures 5 and 6 are side and front elevations,

2

respectively, of the match book arranged as a table place marker or the like.

In general appearance the improved match book resembles the conventional, well known article and it comprises the same essential elements, the match package P, the cover C and staple S. The match package P includes two rows of bendable matches 10, the matches of each row springing from a common web 11 and being readily detachable therefrom. The cover C is an elongated rectangular, flexible sheet, preferably of cardboard and includes the front and back panels 12 and 13, intermediate connecting web 14 and the panel 15 which carries a coating of ignition material. The webs 11 are between the panel 15 and the rear panel 13 and are secured in position by means of one or more staples S which are passed through the four thicknesses of paper. The front and rear panels may be folded into substantial parallelism to close the book (Figure 1), or may be moved into a common plane (Figure 2), or into divergent planes (Figure 5), or into still other angular relationships.

The front panel 12 is cut or incised to provide a tongue 17 which extends longitudinally of the panel, the tongue 17 merging with or joining the body of the panel along the base or hinge line b—b relatively close to the free or unattached end of the panel. Tongue 17 is relatively long and is defined by a group of incisions in end-to-end relationship including the relatively long parallel side incisions 18, the transversely extending terminal incision 19 and the smaller incisions 20 which are spaced from each other and from the longer incisions 18 and 19 so as to leave a plurality of unbroken but relatively weak bridging elements 21 connecting the tip or free end of the tongue and the body of the panel. Bridging elements 21 are broken upon the application of light pressure to the end of tongue 17 and the tongue may be then deflected in either direction, as indicated at 17a and 17b in Figure 3.

Short transverse incisions 23, located upon opposite sides of tongue 17, and extending outwardly from incisions 18 along base line b—b, meet, respectively, the ends of short longitudinally extending incisions 24, the incisions 18, 23 and 24, defining short tongues 25 the free ends of which terminate at base line b—b. Each of these tongues may be laterally displaced by the pressure of a match head, and the end of the match thus caused to penetrate the front panel 12, as shown in Figures 5 and 6, whether or not the tongue 17 has been laterally deflected, tongues 25 then coacting with the adjacent

edges of the panel in frictionally gripping the match stems pushed through the panel. In this manner the front and rear panels may be maintained in fixed relationship (Figures 5 and 6) and the match book may be used as a table place marker; the tongue 17 being used to support a place card 28, or cigarettes 29, or both.

Whether the match book is used in this or in the conventional manner the cover may ultimately be employed as a book mark in the manner indicated in Figure 4, a portion of a sheet of paper being indicated at 30. If the matches have been consumed the end of the cover may be torn off, including webs 11 and panel 15, as shown in Figure 4, but the book may also be used entirely as a book mark, if desired, i. e. in the form in which it appears in Figure 3. It is found that, by reason of the manner in which the front panel is incised at the base of the tongue 17, with the short laterally extending incisions 23 and longitudinally extending incisions 24 supplementing the major incisions 18, the grip of the cover upon a sheet of paper is rendered firmer and more resilient than would otherwise be the case.

Minor changes in the arrangement of incisions and shape of the tongues do not depart from the invention.

Having thus described the invention, what is claimed as new and desired to be secured by Letters Patent is:

1. A match book comprising a package of matches and a cover therefor, the cover being a generally rectangular sheet having generally rectangular front and back panels and a portion connecting the same, said sheet being flexible so that the panels may be relatively folded into substantial parallelism to form a match book of conventional form, or folded into a common plane, the match package being secured to the free end of the back panel and the front panel being incised to provide a tongue adapted to be deflected from the plane of the panel upon the application of slight pressure, said tongue extending longitudinally of the front panel and joining the panel along a base or hinge line within the panel and adjacent the outer end of the panel, the front panel being also transversely incised along said base or hinge line, on each side of said tongue, and longitudinally incised, on each side of the tongue, said longitudinal incisions being relatively short and intersecting the transverse incisions and the transverse incisions intersecting, respectively, those incisions which define the longitudinally extending edges of the tongue adjacent the base thereof.

2. A match book comprising a package of matches and a cover therefor, the cover being a generally rectangular sheet having generally rec-

tangular front and back panels and a portion connecting the same, said sheet being flexible so that the panels may be relatively folded into substantial parallelism to form a match book of conventional form, or folded into a common plane, the match package being secured to the free end of the back panel and the front panel being incised to provide a tongue adapted to be deflected from the plane of the panel upon the application of slight pressure, said tongue extending longitudinally of the front panel and joining the panel along a base or hinge line within the panel and adjacent the outer end of the panel, the front panel being also transversely incised along said base or hinge line, on each side of said tongue, and longitudinally incised, on each side of the tongue, said longitudinal incisions being relatively short and intersecting the transverse incisions and the transverse incisions intersecting, respectively, those incisions which define the longitudinally extending edges of the tongue adjacent the base thereof.

3. A match book comprising a package of matches and a cover therefor, the cover being a generally rectangular sheet having generally rectangular front and back panels and a portion connecting the same, said sheet being flexible so that the panels may be relatively folded into substantial parallelism to form a match book of conventional form, or folded into a common plane, the match package being secured to the free end of the back panel and the front panel being incised to provide a tongue disposed wholly within the panel and adapted to be deflected from the plane of the panel upon the application of slight pressure, said tongue extending longitudinally of the front panel and joining the panel along a base or hinge line within the panel and adjacent the outer end of the panel, said front panel being further incised laterally of said tongue to provide two relatively short narrow secondary tongues the free ends of which are at said base line.
